US00D732026S

(12) **United States Design Patent**
Kim

(10) **Patent No.:** **US D732,026 S**
(45) **Date of Patent:** **** Jun. 16, 2015**

(54) **REMOVABLY ATTACHABLE LENS**

(71) Applicant: **Google Inc.**, Mountain View, CA (US)

(72) Inventor: **Eliot Kim**, Cupertino, CA (US)

(73) Assignee: **Google Inc.**, Mountain View, CA (US)

(**) Term: **14 Years**

(21) Appl. No.: **29/496,595**

(22) Filed: **Jul. 15, 2014**

Related U.S. Application Data

(62) Division of application No. 29/433,056, filed on Sep. 25, 2012, now Pat. No. Des. 712,451.

(57) **CLAIM**

The ornamental design for a removably attachable lens, as shown and described.

DESCRIPTION

FIG. 1 is a front perspective view of a removably attachable lens according to a first embodiment of our design;

FIG. 2 is a front elevation view of the removably attachable lens of FIG. 1;

FIG. 3 is a rear elevation view of the removably attachable lens of FIG. 1;

FIG. 4 is a right elevation view of the removably attachable lens of FIG. 1;

FIG. 5 is a left elevation view of the removably attachable lens of FIG. 1;

FIG. 6 is a top elevation view of the removably attachable lens of FIG. 1;

FIG. 7 is a bottom elevation view of the removably attachable lens of FIG. 1; and,

FIG. 8 is a rear perspective view of the removably attachable lens of FIG. 1.

Broken lines are environmental only and form no part of the claimed design.

Dash-dot lines adjacent un-shaded areas represent bounds of the claimed design and form no part of the claimed design themselves.

1 Claim, 5 Drawing Sheets
